UNITED STATES PATENT OFFICE.

CHARLES THOMAS MASON, OF SUMTER, SOUTH CAROLINA, ASSIGNOR, BY MESNE ASSIGNMENTS, TO SPLITDORF ELECTRICAL COMPANY, OF NEWARK, NEW JERSEY, A CORPORATION OF NEW JERSEY.

IGNITION-DYNAMO.

1,190,785.

Specification of Letters Patent.

Patented July 11, 1916.

Application filed January 25, 1915. Serial No. 4,357.

To all whom it may concern:

Be it known that I, CHARLES THOMAS MASON, a citizen of the United States, residing at Sumter, in the county of Sumter and State of South Carolina, have invented certain new and useful Improvements in Ignition-DYNAMOS, of which the following is a specification, reference being had to the accompanying drawing.

0 My invention relates to ignition dynamos and has for its object the production of a machine of this class which shall be highly efficient in operation, proof against short circuits or other derangement, and of simple and reliable construction.

The present invention is in the nature of an improvement over that described and claimed in Patent No. 1,105,361, granted to me July 28, 1914, and my prior applications Serial Nos. 732,681 and 781,414.

20 In my said patent I have shown and claimed a generator having a primary field, a secondary field structure carrying a generating coil, and a rotor associated with the primary field and adapted to shift the flux therefrom alternately through the opposite members of the secondary field and through the generating coil so as to produce reversal of current therein. The generating coil and its

30 supporting structure and pole pieces were adjustable for timing purposes, being rotated about the axis of the rotor. In my applications above noted a similar structure is described, with certain additions and

35 modifications adapting the machine for commercial use. On the outside of one polar extremity of the primary field, and coaxial with the rotor is an interrupter box capable of being turned with the generating coil,

40 as required for the purpose of timing the spark. The circuit of the coil is carried to its interrupter through a U-shaped connector bar or wire straddling the limb of magnet so as to leave a clearance for travel of

45 the connected parts.

The foregoing arrangement has given excellent results, but I have found it possible to greatly increase the volume of the spark delivered as well as to intensify the same and render it somewhat hotter, by expanding the diametral dimension of each rotor to equal practically the extreme width of the

primary field pole piece with which it is associated. I have also found it desirable to dispense with the exposed U-shaped connecting bar or wire from the coil to the interrupter box and have devised an improved means for connecting these parts through the base of the generator, which enables me not only to simplify the construction, but also to increase the insulation to a point where it is practically impossible to break it down, even with the potentials produced in this machine.

The foregoing points constitute the leading features of improvement which will be described and claimed in this application and ancillary features will sufficiently appear from the detailed description herein-after.

70 My invention is illustrated in the accompanying drawings in which—

Figure 1 is a side view of the machine with parts broken away and in section to show the interior arrangement. Fig. 2 is an end view of the same. Fig. 3 is an opposite end view or elevation. Fig. 4 is a perspective view of the base casting removed. Fig. 5 is a diagrammatic view showing the relation of the rotor members to the field magnets. Fig. 6 is a sectional view showing a detail of the rotor shaft end thrust bearings.

Referring to the drawings and especially to Figs. 1 and 2, M designates the magnetic field structure usually composed of a pair of U-shaped permanent magnets, as indicated in dotted lines in Fig. 2. These are inclosed within end cover plates C, C⁰, a curved top plate C', and side plates C² which are formed up with concavities to permit lateral adjustment of the generating coil G, as the latter is swung from side to side for timing purposes. As this adjustment has been described in my prior Patent No. 1,105,361 hereinbefore referred to, I need only say here that this feature of the operation is the same in the present case. The rotor in this machine consisting of two permanently polarized rotary members, substantially the same as those in the patent referred to, is housed within the magnetic field in a structure R, and the diametral dimensions of the two rotor members are such

that their sum is substantially equal to the greatest width of the magnet poles, or in other words, each rotor element, constituting a permanently polarized extension of one of the poles of the permanent field magnet, in its rotation describes a circle extending entirely across the inner face of the magnet pole or poles. This is indicated by the dotted circle in Fig. 2, and will be clearly understood after reading the patent. It is diagrammatically indicated in the small diagram Fig. 5, one rotor element being indicated at *r* and the coil at *G* and the magnets at *M*, the rotary path of the element *r* being indicated as in Fig. 2 by a dotted circle *R'*.

By reference to Fig. 4, it will be observed that the end plate *C*² is really a part of the base casting *C*³, and upon its outer face carries a flange *c* within which the breaker box *B* is seated, being retained in place by means of the spring *b* carried on the post *b'*.

The numeral 1 denotes a flexible wire or cable connected to the primary terminal 2 of the generating coil *G*. This conductor passes through an insulating tube 3, inserted through openings in the lower part of the base casting *C*³, the rotor casing and the breaker box, and within the latter the other end of the conductor or cable is secured to one terminal of the circuit breaker, as indicated at *b*² in Fig. 3. The other side of the circuit as usual is completed through the frame of the machine, the actual make and break being produced by the cam acting upon the contacts *b*². The breaker box has a laterally projecting arm *b*⁴ for partially rotating the box within the flange *c*, and by means of the sleeve connection *s* between the box and the rotor casing *R*, upon which the generating coil and its structure are mechanically carried, said structure is moved with the breaker box, so that both the generating poles and the circuit breaking contacts are simultaneously and equally adjusted for timing purposes. It will be observed that by the arrangement thus described of the conductor 1 and the tube 3, the external projection of the U-shaped connecting bar is avoided, and since the breaker box and rotor are turned together and always through the same angle, the tube 3, which is bridged from one to the other and supported thereby at its ends, maintains its relative position unchanged although it oscillates through the total angle of timing adjustment, with respect to the base plate and the field magnets. In order to permit this oscillation of the tube 3 and the conductor 1, the opening through the base plate or rather through the end plate *C*, is made in the form of a slot 5 (see Figs. 1 and 4), this slot lying in the arc of a circle concentric with the axis of the rotor and breaker box, and its ends subtending an angle equal to the total

angular displacement of these parts for timing purposes. The generating coil *G* has its windings connected from the terminal 2 on the one side to an external conductor or conductors indicated at *D* on the other side. 70

D may designate the distributor connection or the direct connection to the point of discharge or external circuit control. Inasmuch as the coil, however, is adjustable and not fixed, while the terminal *D* of whatever 75 nature being external, is preferably fixed, and since the potentials generated in the windings of the coil *G* are very high, I provide special means for completing the connection of the coil without substantial leakage. Directly associated with these means is a safety spark arrangement. Said means comprise an insulating bushing 9 fitted into an opening in the side of one of the magnets. Within the bushing is fitted a metal tube 10 80 carrying a sliding brush 11, which bears against and makes sliding contact with the member 12 secured upon the coil and forming the immediate terminal of its secondary winding. A projecting point 13 is formed 90 on the contact 12 at a proper distance from the surface 14 of the frame of the machine and thereby a safety gap of suitable width is provided, between the parts 12 and 14. In order to maintain this gap constant for all 95 positions of the coil upon which the terminal 12 is carried, the surface of the part 14 should have a curvature concentric with the axis of rotation of the coil structure. This however is a detail. The high tension terminal proper comprises the cable conductor 17 connected in suitable manner through the tube 10 to the brush 11, and inclosed within the solid insulation 15 attached by screws or other suitable means to the top of 100 the end plate *C*.

The details of design, dimensions, and specific arrangement of this machine may be varied considerably without departing from the spirit of the present invention, 110 which is characterized particularly by the three features hereinbefore recounted, viz., the large diameter rotor, which covers the entire inner surface of the magnet poles, the inclosed and protected connecting link 3, 115 and the high tension terminal and safety gap *D*, 15, 17, 10, 11, 12, 14. The rotor elements may be made with large hubs, so that flux from the entire inner face of each magnet may be carried without loss to the single projecting extension member, these members for the two elements being of course oppositely placed with respect to the axis of rotation; or each rotor may have oppositely extending rotary arms bridging entirely across the face of its appropriate magnet pole, and only one of said arms carrying a projecting element to co-operate with the coil structure poles. Similarly, the tube 3 and conductor 1 may be carried 120 125 130

across to the breaker box at various other points than the one chosen, so long as they are inclosed within the structure and provision is made for the oscillation of the bridging conductor as by the slot 5. The high tension terminal and safety gap may also be varied in details which will readily occur to those skilled in the art.

In Fig. 6 I have shown a detail of some importance and shall claim the same. This consists in the provision of special means to take the end thrust of the rotor shaft, comprising washers of hard fiber or equivalent material, set into the inner faces of the plates P, P' and surrounding the bearings p, p'. The washers are indicated at W, W', and against each of them rests a shoulder formed on the shaft, as well as the outer face of the rotor member. This feature also can be varied somewhat, without departing from the invention, especially in the dimensions and relations of the parts, so long as the principal purpose is served of having the end thrust taken up without the necessity for accurate facing of the metal parts, which is expensive.

In general, I wish it distinctly understood that all changes and modifications in the devices hereinbefore described, which do not depart from the spirit of the invention, are included within the scope of the appended claims.

Having thus described my invention, what I claim and desire to secure by Letters Patent is:

1. In an ignition dynamo, a magnetic field structure, a rotor, a generating coil structure separate from said rotor, means for shifting flux due to a circuit breaker, and a circuit connection between the coil and the circuit breaker inclosed and concealed throughout its entire length.

2. In an ignition dynamo, a magnetic field structure, a rotor, a generating coil separate from the rotor due to a circuit breaker and a conductor extending from a terminal of the coil to a terminal of the circuit breaker, inclosed throughout its entire length, and protected by a rigid envelop against the movement of adjacent mechanical parts.

3. In an ignition dynamo, a magnetic field structure, a rotor, a generating coil separate from said rotor due to a circuit breaker, a tube extending from the coil structure into the circuit breaker structure, and a conductor connected at one end to a terminal of the generating coil, passing through said tube, and connected at the other end to a terminal of the circuit breaker.

4. In an ignition dynamo, a magnetic field structure, a generating coil structure, means for shifting flux due to the magnetic field, so as to generate electromotive forces in the coil, a circuit breaker, a mechanical connec-

tion between the circuit breaker and the generating coil structure whereby said parts may be angularly displaced around the axis of the flux shifting means for timing purposes, and a conductor extending from one terminal of the generating coil through inclosed portions of the coil structure and the breaker, and connected to a terminal of the latter, said conductor constituting in part a bridge electrically connecting the coil and the breaker and mechanically movable therewith.

5. In an ignition dynamo the combination of the following instrumentalities: field magnets, a rotor composed of permanently polarized elements connected respectively to the poles of said magnets, a generating coil structure having pole pieces adjacent said rotor, a breaker box containing circuit breaking contacts actuated from the rotor shaft, said box lying on the opposite side of one of the field magnet poles from the rotor, a mechanical support for the coil structure with a sleeve connection to the breaker box for simultaneous and angular adjustment, a base supporting the field magnets and associated parts, and a conductor extending from one terminal of the generating coil to a support on the coil structure contiguous to the base, and thence through openings in the base and breaker box, and connected to one of the terminals therein.

6. In an ignition dynamo the combination of the following instrumentalities: field magnets, a rotor composed of permanently polarized elements connected respectively to the poles of said magnets, a generating coil structure having pole pieces adjacent said rotor, a breaker box containing circuit breaking contacts actuated from the rotor shaft, said box lying on the opposite side of one of the field magnet poles from the rotor, a mechanical support for the coil structure with a sleeve connection to the breaker box for simultaneous and angular adjustment, a base supporting the field magnets and associated parts, said base carrying a flange or end plate constituting a support for one field magnet pole and slotted beneath said pole in an arc concentric with the axis of the rotor and breaker box, and a bridging conductor extending from a terminal of the generating coil to a point contiguous to the base but within the magnet pole, and thence through said slot into the bottom of the breaker box, with its end connected to a terminal therein.

7. In an ignition dynamo the combination of the following instrumentalities: a field magnet structure, a rotor, a generating coil structure separate from said rotor, means completely inclosing said elements, a circuit breaker box located on the outside of the inclosure and containing contacts adapted to be actuated from the rotor shaft, and a con-

ductor entirely inclosed throughout its length, connecting a terminal of the generating coil to a terminal in the breaker box.

8. In an ignition dynamo a magnetic field structure, a generating coil structure and a rotor inclosed within the field structure, a breaker box lying outside of the field structure, and non-rotatable mechanical and electrical connections extending directly between the coil structure and the circuit breaker, said electrical connection extending through the supporting means for the mechanical connection.

9. In an ignition dynamo, a field structure, a generating coil structure, and a rotor all completely inclosed, a circuit breaker separately inclosed and located on the outside of the first inclosure, a mechanical connection between the coil structure and the breaker for angular adjustment in timing, and a non-rotatable circuit connection forming a bridge from a terminal of the generating coil to a terminal of the breaker extending through both inclosures, itself completely inclosed throughout its length.

10. In an ignition dynamo, a field structure, a generating coil structure, and a rotor all completely inclosed, a circuit breaker separately inclosed and located on the outside of the first inclosure, a mechanical connection between the coil structure and the breaker for angular adjustment in timing, and a circuit connection forming a bridge from a terminal of the generating coil to a terminal of the breaker through both inclosures, itself completely inclosed throughout its length and having play in the opening in the first inclosure, for mechanical movement in the adjustment of its connected parts.

11. In an ignition dynamo, a field magnet structure, a generating coil structure lying within the field magnet, a rotor having permanently polarized elements constituting continuations of the field magnet poles and driven to shift magnetic flux with respect to the coil structure, a circuit breaker mounted outside of one limb of the field magnet, and a high potential insulated terminal permanently mounted on the outside of the other limb, with a connection through said limb to the generating coil on the inside thereof.

12. In an ignition dynamo, a field magnet structure, a generating coil structure lying within the field magnet, a rotor having permanently polarized elements constituting continuations of the field magnet poles and driven to shift magnetic flux with respect to the coil structure, a circuit breaker mounted outside of one limb of the field magnet, and a high potential insulated terminal permanently mounted on the outside of the other limb, with a connection through said limb to the generating coil on the inside thereof.

side thereof and a safety gap formed by a sparking terminal attached to said connection and spaced a suitable distance from the contiguous portion of the frame of the machine.

13. In an ignition dynamo a field magnet, a generating coil structure and a rotor, said coil and rotor lying inside the field magnet, a high potential insulated terminal secured to the outside of the magnet with an insulated brush extending through the magnet and a coöperating sliding terminal carried on the coil and connected to its windings, together with means for moving said coil and its structure with respect to the rotor, for timing purposes.

14. In an ignition dynamo having a fixed field, a driving rotor and an adjustable generating coil, the combination of an extended terminal connected to and carried by said coil, a coöperating brush terminal fixed to the field structure, insulation surrounding said terminal, and an external conductor connected thereto.

15. In an ignition dynamo, a magnetic field structure, a generating coil carrying an extended circuit terminal, a brush making contact with said extended terminal during movement of the coil, and a coöperating terminal located in contiguity to the extended terminal to form a safety spark gap for the coil in all positions.

16. In an ignition dynamo, a field magnet and generating coil, a terminal for the coil, and an exposed coöperating terminal rigidly supported in contiguity to said coil terminal to form a safety gap.

17. In an ignition dynamo, a field magnet, a generating coil, and a high potential terminal structure for said coil supported on the magnet and comprising an insulated fixed tube or carrier, a spring pressed brush therein, an insulated conductor leading from said tube and brush, and an extended terminal on the coil making contact with the brush throughout the entire range of movement of the coil.

18. In an ignition dynamo, a field magnet, a generating coil, and a high potential terminal structure for said coil supported on the magnet and comprising an insulated fixed tube or carrier, a spring pressed brush therein, an insulated conductor leading from said tube and brush, and an extended terminal on the coil making contact with the brush throughout the entire range of movement of the coil and provided with a projection extending within a proper distance of a portion of the metallic frame of the machine to constitute a safety spark gap in all positions of the coil.

19. An ignition dynamo comprising a field magnet structure having opposite poles, a generating coil structure having coöperating poles between and at an angle

with the field poles, and a rotor comprising permanent polarized elements each constituting an extension of one of the field magnet poles, and each element in its rotation covering a circular area having a diameter equal to the greatest width of its polar face.

20. An ignition dynamo comprising field and coil structures, with a rotor having its 10 axis passing through the field poles and in rotation describing a figure whose ends extend completely across the inner polar faces respectively.

21. In an ignition dynamo a field structure including a core having a winding carried thereby, a rotor having members of permanent and opposite polarity with a shaft journaled in bearings having a fixed relation to the field structure, and supplemental bearings to take end thrust of the 20

shaft consisting of washers surrounding the shaft beside the main bearings.

22. In an ignition dynamo a field structure including a core having a winding carried thereby, a rotor having members of permanent and opposite polarity with a shaft journaled in bearings having a fixed 25 relation to the field structure, and supplemental bearings to take end thrust of the shaft consisting of fiber washers set into 30 the inner faces of the main bearing plates or flanges, the shaft being shouldered at both ends to bear against said washers.

In testimony whereof I hereunto affix my signature in the presence of two witnesses. 35

CHARLES THOMAS MASON.
